UNITED STATES PATENT OFFICE.

ALPIN I. DUNN, OF NEW YORK, N. Y.

AIRSHIP.

Application filed January 30, 1928. Serial No. 84,946.

- The primary object of my invention is to provide an airship of the lighter than air type, embodying means to generate power as the airship travels through the air at speed and to utilize said power either in assisting in the propulsion of the ship or in the accumulation of electric current for general uses on the air-
craft.
- To this end I provide an airship of novel form including a longitudinally extending air tube open at both ends, which tube contains an air motor adapted to be driven by the powerful current of air rushing through said tube during the normal operation of the ship.
- Further objects of the invention are to provide means to increase the pressure of the air in the tube and to close said tube so as to provide a braking effect to stop the ship when desired.
- Further objects will appear as the description of the invention proceeds with reference to the accompanying drawings, in which like reference numerals refer to like parts.
- In said drawings,
- Figure 1 is an elevation of my improved airship.
- Figure 2 is a longitudinal sectional view of the ship.
- Figure 3 is an end view, partly in transverse section.
- Figure 4 is an enlarged sectional view of the rear end of the air tube and the rear propeller.
- Figure 5 is a transverse section on the line 5—5 of Figure 2.
- The airship 1 in which my invention is embodied consists of the usual metal framework parts of which are covered by an envelop impervious to gas, such as helium, or hydrogen, for example. The body of the airship is roughly cigar shaped. Said body is provided with lateral wings 2 and 3, projecting from it in the mid portion thereof. These wings gradually merge into the body of the ship toward each end thereof, as indicated in Figs. 1 and 3. The envelop of the airship is carried over the wing 2 providing a space 5 to receive a quantity of gas and increase the buoyancy of the airship. The lower wing 3 carries pontoon like members 6 on its under surface. These members are covered with an envelop and are preferably filled with gas to further increase the buoyancy of the ship. Suitable struts 7 and braces 8 rigidly secure the wings 2 and 3 together at their outer ends. The lower wing is additionally secured to the framework of the ship by braces 9.
- As will be apparent from Fig. 3 only slightly more than half of the body of the ship is filled with gas. The gas carrying portion is separated from the remainder of the frame by a dividing wall 10. In the lower half of the frame, I may arrange floors 11 and 12. The upper of these floors is arranged to carry the machinery necessary to propel the ship, while the lower floor may be used to carry freight or passengers or both.
- Extending centrally longitudinally of the ship and serving to reinforce the structure of the framework thereof is an elongated tube 13 open at both ends. The forward end of the tube is tapered whereby the pressure of the air that enters the tube at the forward end is increased at the portions that are more restricted in diameter. The taper extends, preferably, throughout nearly one-half the length of the tube as shown at 13' on the drawings. The rearward portion of the tube is of uniform diameter, preferably, and in this portion of the tube I place my air motor.
- Said motor comprises a sectional shaft 14 the ends of the sections being adapted to be connected by clutches 15 so that the shaft may turn as a unit, when the clutches are moved into operative position, or the sections may move independently, when the clutches are disconnected, as will be readily understood. The shaft 14 is supported in bearings 16 provided in the tube (see Fig. 4). Each section of the shaft carries a number of vanes 17, so arranged as to be rotated by the air passing through the tube during the movement of the airship. The vanes are not in alinement but the forward vane is in a different angular position from that immediately behind it, and the same arrangement is followed throughout the entire series, as illustrated in Fig. 5.
- Power may be transmitted to shaft 18 mounted in alinement with shaft 14 and driven through a counter shaft 19 operated by belts 20 running over pulleys 21 (see Fig. 4). Shaft 18 carries a propeller and in this way some of the energy of the fluid motor is used to assist in directly propelling the ship.
- Power is also transmitted from shaft 14 to a generator 22 and the electric current created thereby is stored in storage batteries 23 and may be used for any purpose desired.

- Power is also taken from the same shaft to operate a generator 24 through a clutch 25, the clutch being provided to disconnect this generator when desired. Generator 24, like 5 generator 22 supplies current to storage batteries 23, when it is in operation. On the same shaft with the rotor of the generator is a propeller 26 used to assist in the operation of the airship.
- 10 The airship is started by a propeller 27 operated by a suitable prime mover as will be understood. When the ship is in operation the pressure of the air upon the vanes 17 in the tube will set the air motor in operation 15 providing additional power to assist in the operation of the ship and to charge storage batteries 23, the current of which may be used for any purpose whatever.
- In the forward end of the air tube 13, I 20 may provide a valve 28 of any type to close the tube when desired. In this manner I

may set up a braking action when it is desired to stop the ship.

While I have described the preferred form of my invention in detail, I desire it understood that modifications may be made within the scope of the appended claims.

What I claim as my invention is:

1. An airship comprising a frame, inwardly tapered at its ends, a reinforcing tube 30 extending longitudinally of the frame, wings extending laterally of said frame and merging into said tapered ends, and means to confine gas within the upper portion of said frame and above said wings, and means with- 35 in the lower portion of the frame to carry the machinery and the load of the ship.

2. An airship such as defined in claim 1 in which additional stabilizing wings are provided, said wings carrying pontoon-like 40 envelopes containing buoyant material.

ALPIN I. DUNN.
